UNITED STATES PATENT OFFICE.

JAMES HYMAN BARD, OF JACKSON, TENNESSEE.

HOOP FOR BARRELS, TUBS, &c.

SPECIFICATION forming part of Letters Patent No. 325,809, dated September 8, 1885.

Application filed June 3, 1885. (No model.)

To all whom it may concern:

Be it known that I, JAMES H. BARD, of Jackson, in the county of Madison and State of Tennessee, have invented certain new and useful Improvements in Hoops for Barrels, Tubbs, &c., of which the following is a full, clear, and exact description.

This invention consists in the construction and arrangement of parts, as will be herein-
10 after fully described and claimed.

Reference is to be had to the accompanying drawings, forming a part of this specification, in which similar letters of reference indicate corresponding parts in all the figures.

15 Figure 1 represents a side view of a barrel or cask in part with my invention applied; Fig. 2, a perspective view of the hoop detached, and Fig. 3 a perspective view of a spacing-sleeve used in connection with the hoop.

20 A indicates the barrel or cask in part, and B one of my improved hoops for securing the same. Said hoop B, which may be made of galvanized or other wire, and of which there may be any number on the barrel or other 25 article of wooden-ware, and which may be made of different sizes and thicknesses of wire according to the size, &c., of the vessel to be hooped, is locked at its meeting-end portions by forming the same with a bend, as at b, 30 and coils c at the extremities of the wire upon each side of the bend. This construction provides for a tight and secure lock of the hoop, and so that the hoop may be driven onto the vessel with all the force that can or- 35 dinarily be exerted and still the splice remain intact. As, however, it is desirable that the hoop should be made adjustable, the splice formed, as described, is so wrapped on each side of the lap between the two coils, c, as to 40 leave a space, s, between its wrapping portions, which will leave the coiled ends free to slide to or from each other, thus making the

hoop larger or smaller, as required. The proper size of the hoop being ascertained, (and a smaller one than would be necessary under a 45 different construction may be used,) a spacing-sleeve, C, which may be formed of a wedge-shaped or tapering piece of sheet metal, is inserted at its narrowest end through the space s, between the coils c the proper distance, and bent or wrapped around the terminal portion of the wire, as shown in Fig. 1, thus forming a sleeve that prevents the wraps from approaching beyond their proper limit, thereby holding the locked hoop at its adjustment. 55

In order to apply my hoop to a barrel or other vessel, a hoop of the proper size is selected and placed around the staves, and a sleeve, C, driven into the space s to cause the hoop to be drawn tightly to its place. In 60 some instances the hoop will fit the barrel sufficiently close to render the use of the sleeve C unnecessary, in which case the inner ends of the two coils will contact when the hoop is driven upon the barrel, but the hoop will not 65 stretch at the joint, owing to the construction thereof.

Having thus described my invention, I claim as new and desire to secure by Letters Patent—

1. In a hoop for barrels, tubs, &c., made of wire the construction of the extremities of the wire with a lock, substantially as described, the same consisting of a bend of each wire and a coil of the extremities of the wire loosely fitting upon each side of the bend, as 70 set forth.

2. The combination, with the hoop between the two coils, of a spacing-sleeve, substantially as and for the purpose herein described.

JAMES HYMAN BARD.
